UNITED STATES PATENT OFFICE.

RICHARD WUCZKOWSKI, OF VIENNA, AUSTRIA-HUNGARY.

CONSTRUCTION OF FERROCONCRETE TRUSSES, GIRDERS, AND THE LIKE.

1,153,411.

Specification of Letters Patent. Patented Sept. 14, 1915.

Application filed January 27, 1914. Serial No. 814,627.

To all whom it may concern:

Be it known that I, RICHARD WUCZKOWSKI, subject of the Emperor of Austria-Hungary, residing at Hegergasse 8, Vienna, Austria-Hungary, have invented certain new and useful Improvements in the Construction of Ferroconcrete Trusses, Girders, and the like, of which the following is a specification.

10 The present invention relates to a new construction for ferro-concrete trusses, girders and the like which may be subjected to bending strains; a peculiar formation of the compression straps and compression trajectories of the truss insures the provision of a truss which is almost independent of the quality of the concrete in which it is embedded and furthermore possesses increased supporting power. These objects are attained according to the present invention by building into the truss in the direction in which its compression straps and compression trajectories run, cores of a building material capable of withstanding pressure 25 and connecting the cores with the tie rods of the truss by means of suitable connecting elements.

30 The new method of building is illustrated in the accompanying drawings by various structures that may be subjected to bending strains such as girders, trusses, arches and the like.

Figure 1 is an elevation of a portion of a composite girder constructed according to this invention, the concrete surrounding the trussing being removed to show the structure. Fig. 2 is a side elevation of the left hand support of the composite girder. Figs. 3, 4, 5 and 6 are sections on the lines 35 III-III, IV-IV, V-V and VI-VI of Fig. 1. Figs. 7 and 8 show in elevation two lattice or trussed girders constructed according to this invention. Fig. 9 shows the formation of a truss without diagonals (Vierendeel system). Fig. 10 shows the formation of a hollow truss. Figs. 11 and 12 show in elevation and section details of the portion marked XI of the trussed girder shown in Fig. 7. Figs. 13 and 14 show 40 in elevation and section details of the portion marked XIII of the trussed girder shown in Fig. 7. Figs. 15 and 16 show in elevation and section details of the portion marked XV of the trussed girder shown in Fig. 8. Figs. 17 and 18 show in elevation

and section details of the portion marked XVII of the lattice girder shown in Fig. 8. Fig. 19 shows diagrammatically the formation of an arch according to this invention. Fig. 20 is a transverse section of a short or shallow arch. Fig. 21 is a transverse section of a long or deep arch. Figs. 22, 23 and 24 show in perspective various elementary thrust resisting members for the cores. Figs. 25, 26 and 27 show diagrammatically the method of constructing a composite girder as shown in Fig. 1 of the drawing.

Before the method of construction of the new girder is more fully described the trussing thereof will be described first from a purely constructive point of view. The composite girder shown in Figs. 1 to 6 has in its upper part a core α which runs in the direction of its compression strap and will hereinafter be briefly termed the "compression strap core".

Against the compression strap core α bear a series of cores γ which run in a diagonal direction and also in direction of the thrust trajectories of the girder and will be hereinafter briefly termed the "thrust trajectory cores". The compression strap cores and the thrust trajectory cores are composed, in the constructions shown in the drawings of a number of compression resisting members of a building material (such as natural or artificial stone) which is capable of resisting pressure.

The tie bars z of the composite girder are arranged in the lower arch and consist in the construction shown in Fig. 1 of three rows of round bar iron $z^1, z^2, z^3, z^4, z^5, z^6, z^7, z^8, z^9$, (see Fig. 6) arranged one above the other. The thrust trajectory cores bear with their undersides against a thrust member 2 lying upon the tie bars z and provided with projecting heads (see Fig. 2). At the other end of the thrust trajectory cores is provided a thrust member 7 provided with wedge-shaped surfaces, which bears on one side against the thrust member 2 of the compression strap core α and on the other against a downwardly extending bearing surface 8 on the thrust member.

The tie rods z are connected by suitable means to the compression strap core α and the thrust trajectory cores γ of the girder. The connection of the tie rods to the compression cores of the girder may be effected in various ways, for example by anchoring

the ends of the tie rods to or in the thrust members of the cores. In the construction shown in Fig. 1 the outer tie rods z^1 , z^3 are anchored to a thrust member 2 of the thrust trajectory core y which thrust member as shown in Fig. 2 is provided with projecting heads. The central tie rod z^2 is anchored in the manner shown in Fig. 2 to the thrust trajectory core y itself. The outer tie rods z^4 , z^6 of the second row are anchored to a thrust member 2 of the compression strap core (see Fig. 3) while the central tie rod z^5 is anchored to a bolt 3 (see Fig. 3) which is carried by the ends 4 of the tie rods z^4 , z^6 which are bent around to form hooks. The tie rods z^7 , z^9 are anchored in the manner shown in Fig. 5 to a thrust member 2 of the compression strap core x provided with projecting heads, while the central tie rod z^8 is anchored to a ring 5, (see Fig. 5) which is carried on the end thrust member 7 of the thrust trajectory core. The compression strap core and if necessary the thrust trajectory core also, is wound around with a trussing of any desired form, consisting of a longitudinal trussing 10 with a transverse trussing 11 suitably arranged closer thereto. The construction and formation of this trussing must be made to suit the particular strain to which the structure is to be subjected.

The construction of composite girders of the structure hereinbefore described may be carried out in various ways. A particularly suitable method of construction for the production of such composite girders will be described with reference to Figs. 25, 26 and 27. In this method of construction core pieces x^1 are first formed from a number of elementary thrust members 1. This is most simply effected by inclosing a group of thrust members 1 ranged loosely alongside each other in an angle iron framework 20 (see Fig. 25) and by winding this framework around with wire. The number of thrust trajectory cores y^1 required for the composite girder is next formed in exactly the same way. When this has been done the compression strap cores and the thrust trajectory cores are laid upon a board 21 and the spaces between the compression cores x^1 , x^2 , x^3 filled up with supporting or anchoring thrust members 2. The tie rods z of the composite girder are next anchored in the manner already described to the compression cores of the girder, the compression bars and tie rods if necessary interlaced with each other and the girder trussing so obtained inclosed by the walls 22, 23 of the mold. The mold 21, 22, and 23 with the girder trussing inclosed therein is then set up in a vertical position and the mold filled up with concrete in the well known manner which completes the process of production of the composite girder.

An important advantage of the girder so constructed is that the strains in it which are set up in the pressure zones are absorbed by thrust members of previously selected elasticity of compression, while in girders of the normal structure the strains which are set up in the pressure zones have to be absorbed by the concrete itself. By the building in of cores made of building materials which are capable of resisting pressure and follow the direction in which the compression straps and thrust trajectories run, there is therefore provided a truss which is completely independent of the quality of the binding power of the concrete. The only duty of the concrete in the new truss construction is to inclose the tension members and thrust members of the girder, to give it the usual appearance and to increase its fire resisting powers.

Composite girders constructed as above described can be produced with considerably reduced cost of construction for the same supporting power and if made at the same cost of construction yield a greatly increased supporting power.

The above described structure of truss may also be employed with suitable changes in the arrangement of the compression straps and thrust trajectory cores for trusses, columns, arches and the like which are subjected to eccentric strains and examples of such trusses are diagrammatically shown in Figs. 7, 8, 9 and 10 of the drawing. In these figures the compression straps and thrust trajectory cores are denoted by x throughout, the thrust cores being shown for the sake of clearness as homogeneous core pieces with the omission of all longitudinal and transverse trussings. The tie rods are indicated by dot and dash lines z , and in like manner, for the sake of clearness the special means for connecting the tie rods with the thrust cores and the formation of the so-called knots of the truss are not shown in full. The formation of the knots of the truss may be effected in various ways. The knot formations shown in Figs. 11 to 18 are only given by way of examples of specially suitable constructions.

The connection of the tie bars at the knot XI of the truss shown in Fig. 7 is effected by a shoe-shaped iron structure 31 mounted on the connecting thrust member 30, to which the tie rod z of flat or otherwise suitably shaped iron is riveted. The shoe 31 itself consists of two plates 32, 33 between and to each of which are riveted bearing plates 34, 35 bearing upon the anchoring compression strap 30. The tie rod connection at knot XIII of the truss shown in Fig. 7 is likewise effected by a shoe 40, into which the lowest thrust member x^n of the thrust trajectory core is inserted. The shoe 40 itself consists of two plates 41, 42 which

are built in between the tension straps α and are riveted by means of angle irons to the tension straps. The tension trajectory member α running toward the knot XIII is attached to the tension straps α in the manner shown in Fig. 13. The knot formation shown in Figs. 15 and 16 (knot XV, Fig. 8) is constructed in a similar manner to the knot XI. The only difference between 10 it and the latter is that a suitably constructed anchoring shoe 50 is provided with means such as studs 51 to which are attached round bar iron or cable tie rods Z. In like manner the tie rod connection XVII 15 (see Figs. 17 and 18) of the truss shown in Fig. 8 of the drawing is constructed in a similar manner to the knot XIII (see Fig. 13). The above described details of constructions of the knot formations are only 20 intended to illustrate the possibility of a statically secure ligature between the compression straps and the thrust trajectory cores. The formation of the connections themselves may be varied as desired without departing from the invention. 25

The invention may also be applied with advantage to truss constructions which are subjected to eccentric pressures and examples of such structures are illustrated in 30 Figs. 9, 10, 19, 20 and 21 of the drawings. Fig. 9 shows a truss without diagonals (a so-called Vierendeel girder) constructed according to this invention. Fig. 10 shows the structure of a one or more storied hollow truss, while Figs. 19, 20 and 21 show in elevation and transverse sections the formation of shallow and deep arches according to this invention. The trussing of 35 these structures will be at once understood 40 on reference to the drawings, if it be remembered that in these drawings the core trussings arranged in the pressure zones of the structure and composed of a building material capable of resisting or withstand- 45 ing pressure are denoted by α and the tie rods arranged in the tension zones by α . When the present invention is applied to 50 hollow and girder trusses the solid arches and compression straps required in such trusses when the usual ferro-concrete building methods are employed may be dispensed with, without the supporting power and 55 structure of the truss constructions being unfavorably affected.

The material of the thrust core trussing, the form and formation of the elements of the thrust cores composing the thrust members and also their assemblage and the nature of their material may be varied as

desired without departing from the present 60 invention.

Having thus described my invention and explained the mode of operation thereof, I claim and desire to secure by Letters Patent:

1. In reinforced concrete construction, 65 a compression strap core comprising a substantially continuous member formed of a series of independent members or elements juxtaposed end to end, a thrust trajectory core comprising a continuous member formed 70 of individual members or elements placed end to end, said thrust trajectory core extending at an angle to and engaging said compression strap core, and metallic tie bars for firmly connecting said cores to each 75 other.

2. In reinforced concrete construction, a compression strap core comprising a series of like members or elements arranged end to end to form a continuous core, thrust 80 members between certain of said core members, each of said thrust members having projecting heads, a thrust trajectory core comprising a plurality of independent members or elements placed end to end and 85 forming a continuous series extending at an angle to the compression strap core and tie bars engaging said thrust trajectory core and the projecting heads of the thrust members in said compression strap core. 90

3. In reinforced concrete construction, a compression strap core consisting of a plurality of separate pressure resisting members arranged end to end to form a substantially continuous series, thrust members interposed 95 at intervals between certain adjacent members of said compression strap core, thrust trajectory cores each arranged at an angle less than a right angle to the compression strap core, each of said thrust trajectory 100 cores comprising a plurality of separate members or elements arranged end to end to form a continuous series, a wedge shaped thrust member between the adjacent surfaces of each thrust trajectory core and the 105 compression strap core, said thrust members having one surface bearing against the compression strap core proper and another surface bearing against one of the thrust members of said compression strap core, and 110 metallic tie bars for connecting said entire structure together.

In testimony whereof I affix my signature in presence of two witnesses.

RICH. WUCZKOWSKI, ING.
